Specification of Letters Patent. Patented Oct. 26, 1919.

Application filed February 7, 1916. Serial No. 76,637.

To all whom it may concern:

Be it known that I, ALPHONS P. M. WILKING, a subject of the Queen of Holland, now residing in the city of Trenton, in the county of Mercer and State of New Jersey, have invented an Improvement in Presses, of which the following is a specification.

This invention relates generally to improvements in presses and more particularly to improvements in fluid pressure presses. The present invention will find its most general application in presses which are particularly adapted for use in vulcanizing rubber articles, such presses being commonly provided with relatively movable, heated platens. The principal object of the invention is to provide a press which will be simple in construction and efficient in operation and wherein a single motive power may be employed for accomplishing the dual purpose of heating the platens of the press and bringing them together to apply the requisite pressure to the mold-contained articles placed therebetween. Further objects of the invention will be in part obvious and in part pointed out in the following specification. The invention accordingly consists in the features of construction, combinations of elements and arrangement of parts which will be exemplified in the structure herein-after described.

One embodiment of the invention has been selected for purposes of illustration and description, the same being shown in the accompanying drawings, wherein—

Figure 1 is a front elevation;

Fig. 2 is a top plan view;

Fig. 3 is a vertical cross section on the irregular line 3—3 of Fig. 2, on a slightly reduced scale; and

Fig. 4 is a detail section, later to be referred to, on the line 4—4 of Fig. 3.

The press shown in the accompanying drawings is particularly adapted for use as a vulcanizer press and will be so referred to in the following description. This press comprises relatively movable platens 1 and 2 of which the former may be fixed as shown and the latter may be movable. The fixed platen 1 is held in fixed relation to the base 3 of the machine by suitable stud bolts 4 and its position in relation thereto is susceptible of adjustment by suitable means

herein shown as lock nuts 5 and 6 above and below the fixed platen.

Means may be provided to cause the movable platen 2 to move toward or away from the fixed platen 1 when under control by a suitable motive power, the construction herein provided to accomplish this result being shown as a fixed piston 7, of which the base 3 forms an outwardly extending flange. Mounted upon this fixed piston is a movable cylinder 8, of which the movable platen 2 forms a cylinder head. If desired, this cylinder may be suitably jacketed as by a cylindrical jacket 9 to decrease the loss of heat and power through radiation.

It has been heretofore customary in this art to provide two separate and distinct motive powers one for applying the necessary pressure by causing the platens of a vulcanizer press to be brought together and the other for heating the platens to provide the necessary heat for vulcanizing the rubber. Commonly, hydraulic power is used for pressing the platens together and steam is used for heating the platens. In this invention I contemplate the use of a single motive power for accomplishing this dual purpose and the construction and arrangement of the parts herein provides one means for causing a single motive power to accomplish this dual purpose. Herein the requisite pressure and heat are both obtained by the use of steam as a motive power.

Referring again to the drawings and particularly to Fig. 3, it will be seen that a steam space 10 within the cylinder is located in sufficient proximity to the surface of the fixed platen to cause the steam there introduced to heat the fixed platen and thereby apply the requisite heat to the mold which may be inserted between the platens, although, if desired, this fixed platen may be cored out and an annular chamber 11 formed therein to bring the steam still nearer to the surface of the movable platen. Preferably this chamber is connected with the steam space 10 by a port 12. It will be seen that the heating and moving of the platen 2 is accomplished without the use of any flexible or movable steam connection.

Means may be provided to heat the fixed platen, the same being herein shown as an annular chamber 13 cored out of the platen,

adapted to have steam introduced thereto to provide the requisite heat.

Steam connections for the vulcanizer unit are provided through a pipe 14 threaded in 5 the fixed piston 7, a pipe 15 threaded in the fixed platen 1 and connected with the steam pipe 14 through pipes 16 and 17 and suitable elbow and T connections. Pipes 18 and 19 provide a steam connection to a means for 10 controlling the admission and exhaust of steam herein shown as a three-way valve 20. A pipe 21 leads from the three-way valve 20 to a suitable source of steam supply and a pipe 22 is provided for exhaust steam. It 15 will be observed that the steam connections are made only to fixed parts of the vulcanizer press.

The three-way valve 20 is provided with an annular valve member 23 having a port 20 24 to register alternatively with ports 25 and 26 in the body of the valve. The annular valve member is further provided with a port 27 to register alternatively with the port 26 or port 28 in the body of the valve. 25 These details are shown in Fig. 4 which is a cross section of the valve on the line 4-4 of Fig. 3. Suitable means may be provided for operating the valve, the same being herein shown as a simple lever arm 29 fast to the movable valve member 23 and having a pin 30 slidable in a slot 31 to limit the movement thereof.

In operation it is customary to fill a suitable mold having one or more mold cavities, 35 with unvulcanized rubber and thereupon to insert the mold between the platens of a vulcanizer press. This particular embodiment of the invention, as shown in the drawings, is set to receive the mold, the three-way valve being in position to open the steam pipe 19 and through it the steam space within the cylinder, to exhaust. Hence, the movable cylinder is allowed to assume its normal position as shown. When the filled mold has 40 been placed between the platens of the press, the three-way valve may be rotated (contraclockwise in Fig. 4) to connect the vulcanizer press with the steam supply pipe 21 by causing the ports 24 and 27 of the movable member to register respectively with the ports 25 and 26. This causes steam to be introduced to the steam space 10 within the cylinder and to the steam chamber 13 within the fixed platen. If the movable platen 45 is chambered the steam will also be admitted to the chamber 11. This causes the movable platen to approach the fixed platen and simultaneously heats both platens. The mold with is unvulcanized rubber is then 50 subjected to the requisite pressure and heat for a sufficient period of time to accomplish the complete vulcanization of the rubber contained in the mold and at the end of this period the three-way valve may again be 55 operated to connect the pipe 19 with the pipe

22 to exhaust the steam from the vulcanizer unit whereupon the cylinder 8 will assume its normal position and the mold may be removed from the press and the operation repeated.

It will be seen from the foregoing that this invention, and particularly the above described embodiment thereof, provides a simple efficient press free from complications in construction and organization and one which will prove economical and efficient in operation.

The invention may be variously embodied within the scope of the subjoined claims.

I claim as my invention:

1. In a press of the character described, the combination of relatively movable platens, a steam cylinder for the introduction of steam to move one of said platens, and a chamber within the other platen for the admission of steam to heat said platen.

2. In a press of the character described, the combination of relatively movable platens, a steam cylinder having a steam space adjacent one of said platens for the introduction of steam to move and heat said platen, and a chamber within the other platen for the admission of steam to heat said platen.

3. In a press of the character described, the combination of relatively movable platens, and a steam cylinder having a cylinder head forming one of said platens and having a steam space within said cylinder adjacent said platen.

4. In a press of the character described, the combination of relatively movable platens, a steam cylinder having a cylinder head forming one of said platens and a steam space within said cylinder adjacent said platen, and means to conduct a heating fluid to the other platen.

5. In a press of the character described, the combination of a fixed piston and a movable cylinder, the cylinder head thereof forming one of a pair of platens, a second platen mounted in fixed relation to said piston, and means to introduce an actuating fluid to the interior of said cylinder to bring the platens together.

6. In a press of the character described, the combination of a fixed piston and a movable cylinder, the cylinder head thereof forming one of a pair of platens, a second platen mounted in fixed relation to said piston, means to introduce an actuating fluid to the interior of said cylinder to bring the platens together, and means to conduct a heating element to the platens.

7. In a press of the character described, the combination of a fixed piston and a movable cylinder, the cylinder head thereof forming one of a pair of platens, a second platen mounted in fixed relation to said piston, means to introduce an actuating

fluid to the interior of said cylinder to bring the platens together, and means to cause the actuating fluid to heat the platens.

8. In a press of the character described, 5 the combination of a fixed piston and a movable cylinder, the cylinder head thereof forming one of a pair of platens, a second platen mounted in fixed relation to said piston, a chamber within said fixed platen 10 having an operative connection with the interior of said cylinder, and means to admit steam to the interior of said cylinder to heat the platens and to bring them together.

9. In a press of the character described, 15 the combination of a fixed piston and a movable cylinder, the cylinder head thereof forming one of a pair of platens, a second platen mounted in fixed relation to said piston, a chamber within said fixed platen, 20 and means controllable to admit steam

simultaneously to said chamber and to the interior of said cylinder.

10. In a press of the character described, 25 the combination of a fixed platen, a movable platen, an actuating piston and cylinder for said movable platen having a steam space adjacent the surface of said movable platen, a chamber within said fixed platen forming a steam space adjacent the surface thereof, means connecting said steam spaces, and 30 means providing an exhaust port below the level of said steam spaces, said steam spaces and connections being constructed and arranged to drain water of condensation to said exhaust port. 35

In testimony whereof, I have signed my name to this specification this fourth day of February, 1916.

ALPHONS P. M. WILKING.
